UNITED STATES PATENT OFFICE.

JOHN F. O'CONNOR, OF CHICAGO, ILLINOIS, ASSIGNOR TO WILLIAM H. MINER, OF CHAZY, NEW YORK.

SHOCK-ABSORBING MECHANISM.

1.290,311.

Specification of Letters Patent.

Patented Jan. 7, 1919.

Application filed March 23, 1917. Serial No. 156,918.

To all whom it may concern:

Be it known that I, JOHN F. O'CONNOR, a citizen of the United States, residing at Chicago, in the county of Cook and State 5 of Illinois, have invented a certain new and useful Improvement in Shock-Absorbing Mechanism, of which the following is a full, clear, concise, and exact description, reference being had to the accompanying drawings, forming a part of this specification.

My invention relates to improvements in shock absorbing mechanism.

The object of my invention is to provide a simple and efficient shock absorbing mechanism, and one more particularly adapted for railway draft riggings.

In the drawings forming a part of this specification, Figure 1 is a side elevation, partly in vertical longitudinal section, of 20 a draft rigging embodying my invention. Fig. 2 is a horizontal section, taken on the line 2—2 of Fig. 1. In Figs. 1 and 2 the parts are shown in normal position. Fig. 3 is a horizontal section showing the position 25 of the parts in full compression in buffering movement. Fig. 4 is a cross section, taken on line 4—4 of Fig. 1. Fig. 5 is a perspective view of one of the wedges, and Fig. 6 a perspective view of one of the friction shoes.

Referring to the drawings, the numeral 10 indicates draft members, as for instance, center sills, being the parts of the car under-frame, to which the draft rigging is applied; 11—11 the front stop members appropriately secured to the draft members, as for instance, by the rivets 12; 13—13 the rear stop members similarly secured, as for instance, by the rivets 12 to the draft members. A draw bar is indicated at 14 and to 40 this is attached by any suitable means, as for instance the rivets 15, and yoke 16. A draft gear 17 is mounted between the draft members and includes the shell 18, which in preferable construction is rectangular in 45 cross section, as clearly shown in Fig. 4 of the drawing. The said shell is hollow and open at both ends. Mounted forwardly of the shell and adapted to engage the front stop members, is the front follower 19 and rearwardly of the shell, the rear follower 20, both inclosed within the yoke 16.

Mounted within the shell are two sets of friction plates 21—21 and arranged on either side thereof. Between the said sets of

plates are mounted the central friction elements 22. Each set of friction plates comprises a plurality of preferably flat members, alternately arranged, the alternate plates at one end projecting forwardly and being engaged to the front follower, as indicated at 23—23, the other alternate plates projecting rearwardly and being engaged to the rear follower, as indicated at 24—24. Front and rear keys 25 and 26, respectively, suitably spaced apart, are mounted within 65 the casing 17 extending transversely thereof and enter at their ends the slots 27—27 provided within the casing. The said keys also pass through elongated slots 28—28 provided in the friction plates 21.

As will be hereinafter described, the said friction plates have a sliding action upon each other and upon the shell, means for compressing them against each other being found in the central friction elements 22. 70 The central friction elements comprise the friction shoes 29—29, each having front and rear internal wedging faces 30 and 31, respectively, and outer friction faces 32 adapted each to engage against an adjacent friction plate. The said friction shoes are both 75 forwardly and rearwardly provided with the transverse slots 33 for the passage, respectively, of the front and rear keys 25 and 26.

The front and rear wedges 34 and 35, respectively, are provided each with the wedging faces 36 adapted to engage against the adjacent wedging faces of the friction shoes. Each of the wedges 34 and 35 is provided 80 with a transverse slot 37, the slot in the wedge 34 accommodating the key 25 and the slot in the wedge 35 accommodating the key 26. The slots 37 within the wedges are of a greater longitudinal dimension than the 85 width of the key passing therethrough, in order to permit longitudinal movement of the wedge upon the key. An internal follower 40 engages the head of the front wedge 34, and is preferably, as shown in 90 Fig. 5 of the drawings, integral therewith. This, for convenience, we may designate the front internal follower, and a rear internal follower 41 is associated with the head of the rear wedge 35 and is preferably integral 95 therewith. Springs 42 are mounted between the front internal follower 40 and the front follower 19, and springs 43 are mounted be-

tween the rear internal follower 41 and the rear follower 20. The front and rear followers are each provided with the laterally extended wings 44 adapted to pass through 5 slots 45 in the friction plates, in order to connect the friction plates with the followers, and at their ends the said followers are adapted to engage the stops in a manner that will be readily understood.

10 The draft gear is supported upon the sills by means of the carrier-plates 46-46, which are preferably removably secured to the sills or draft members by means of the bolts 47-47.

15 On rearward movement of the draw bar, the front follower drives the friction plates, with which it is associated, rearwardly and compresses the front spring 42, the front spring acting against the front wedge 34, the 20 said wedge riding rearwardly upon the front key 25 and forcing the friction shoes 29 outwardly, the said shoes in their lateral outward movement sliding upon the keys 25 and 26 and being also wedged against by the 25 rear wedge 35, the rearward movement of which is resisted by the rear springs 43, the said rear springs being held against rearward movement by the rear follower 20, the said rear follower being stopped by the rear 30 stop members 13.

As the front friction plates move rearwardly they slide between the alternately arranged friction plates which are secured to the rear follower and stopped thereby, 35 and frictional action in each set of plates is afforded through the outward pressure of the friction shoes 29 which press the plates between them and the adjacent sides of the shell 18.

40 Upon full rearward movement of the parts, they assume the relative positions illustrated in Fig. 3 of the drawings. The shell, which may also move longitudinally on full buffering movement, engages the rear follower, and the front follower will come into engagement with the front end of the shell.

45 On forward movement of the draw bar, the operation of the parts is substantially the same, the yoke drawing the rear follower forwardly, the rear springs, under compression between the rear follower and the rear wedge, forcing the rear wedge forwardly, and this action together with the spreading action of the front wedge, which is resisted 50 by the front springs seated against the front follower, spreads the friction shoes and the relatively longitudinally moving friction plates are pressed between the friction shoes and the shell in the same manner as in buffering action of the gear.

55 It will be observed that the keys 25 and 26, being mounted within the shell and associated with the springs, serve, with the springs, to return the floating friction shell 60 to its normal position.

I claim:

1. In a shock absorbing mechanism, in combination: a shell; alternately arranged, overlapped friction plates within the shell; friction elements including wedging means 70 disposed midway of the length of the shell and between the overlapped portions of said plates; keys mounted within the shell; the said friction elements being provided with actuating means and being mounted upon 75 said keys.

2. In a shock absorbing mechanism, a combination: a shell; followers associated therewith; friction plates within the shell, each secured to one of said followers and 80 having a sliding action on each other; keys mounted in the shell; friction elements adapted to press the friction plates between them and the shell; means to transmit motion from the followers to the friction elements, the said friction elements being slidably mounted upon the keys. 85

3. In a shock absorbing mechanism, in combination: a shell; followers associated therewith; friction plates within the shell, 90 each plate being secured to a follower; friction shoes and wedging members therefor associated with the plates; and a spring mounted between each of said wedging members and the adjacent follower to which the 95 friction plates are secured.

4. In a shock absorbing mechanism, in combination: a shell; a set of friction plates within the shell and on either side thereof; friction elements mounted between the said 100 sets of plates; keys mounted within the shell and supporting the said friction elements therein; followers at either end of the shell; and means interposed between the followers and the friction elements whereby the friction elements may be spread to press the friction plates between them and the shell. 105

5. In a shock absorbing mechanism, in combination: a shell; followers associated with said shell; friction plates mounted 110 within the shell; each of said plates being secured to a follower; friction elements associated with said plates; keys mounted within the shell; springs interposed between the followers and the friction elements, said 115 friction elements comprising wedging members slidably mounted upon said keys and adapted to compress the friction plates against each other.

6. In a shock absorbing mechanism, in 120 combination: a shell; a plurality of sets of friction plates mounted therein; friction elements mounted between said sets of plates; front and rear followers associated with said shell; keys mounted within the shell and 125 rigidly secured thereto; springs between the followers and the friction elements; each of the friction plates being secured to a follower; the friction elements comprising 130 shoes and wedging members therefor; the

shoes being slidably mounted upon the keys; and the wedging members being actuated by the springs.

7. In a shock absorbing mechanism, in combination: a shell, a plurality of sets of friction plates mounted within the shell; spreading members adapted to compress said plates mounted between the sets thereof; followers at either end of the shell; springs seated between the followers and the spreading members; keys supporting the spreading members, the said keys being rigidly secured to the shell.

8. In a shock absorbing mechanism, in combination: a shell; keys mounted within the shell and rigidly secured thereto; followers associated with said shell; friction plates alternately secured to said followers and slidingly associated with said keys; friction members to compress the friction plates; and means mounted between the friction members and the followers to impart the movement of the followers to said friction means.

25 9. In a draft rigging for railway cars, in combination: draft members; stop members associated therewith; a draft gear; a draw bar; means for connecting the draft gear to the draw bar; the draft gear including a shell slidingly mounted between the draft members; followers associated with said shell; keys transversely arranged in the shell; friction plates connected to the followers; friction members adapted to compress the friction plates together and against the shell; springs mounted between the friction elements and the followers; the friction elements comprising shoes engaging the friction plates; and wedges adapted to spread 40 said shoes.

10. In a draft rigging for railway cars, in combination: draft members, a draft gear mounted between said members; stop members for the gear associated with the draft members; followers associated with the draft gear; the draft gear including a shell; friction plates therein; friction members adapted to compress said plates into frictional engagement with each other; the said 50 followers actuating the friction plates directly and actuating the friction members by spring means associated therewith.

11. In a draft rigging for railway cars, in combination: draft members; a draft gear mounted between said members; followers associated with said draft gear; the draft gear including a shell; alternately ar-

ranged friction plates connected to the followers and within said shell; friction members adapted to impinge said plates against the shell; and means for returning the parts to their normal position, said means including springs associated with the followers; and keys rigidly connected to the shell.

12. In a draft rigging, in combination: a shell; front and rear followers associated therewith; friction plates extended from each of said followers and having sliding action on each other; friction elements mounted within the shell and adapted to hold said plates in frictional engagement with each other; means associated with the followers for actuating the friction elements; the said shell being spaced apart from the said followers in normal position of the gear.

13. In a draft rigging for railway cars, in combination: a shell; followers associated therewith; alternately arranged friction plates mounted within the shell, each being extended from one of the followers; friction elements associated with said friction plates to compress the same into engagement with each other; members rigidly connected with the shell; springs mounted between the friction elements and the followers; the shell being spaced from the followers in normal position; the said springs being adapted to act against said rigid connecting means to return the shell to normal position.

14. In a friction shock absorbing mechanism, the combination with a shell, of two sets of friction plates, one set being extended beyond one end of the shell and the other set beyond the other end of the shell, the plates of one set being alternated with the plates of the other set and overlapping within the shell, means for preventing movement of one set of plates relatively to the shell in one direction from normal, means for preventing movement of the other set of plates relatively to the shell in the opposite direction from normal, devices for creating lateral pressure exerted against the overlapped portions of the sets of plates, means associated with each set of plates for actuating the latter relatively to the shell, and springs interposed between said means and said devices.

In witness that I claim the foregoing I have hereunto subscribed my name this 20th day of Mar., 1917.

JOHN F. O'CONNOR.
